W. E. Doubleday,

Pressing Hats.

No. 58,391.

Patented, Oct. 2, 1866.

Chas A. Smith

GEO. D. Walker

W. E. Doubleday

UNITED STATES PATENT OFFICE.

WILLIAM E. DOUBLEDAY, OF BROOKLYN, NEW YORK.

IMPROVEMENT IN MAKING HATS.

Specification forming part of Letters Patent No. **58,391**, dated October 2, 1866.

To all whom it may concern:

Be it known that I, WILLIAM E. DOUBLEDAY, of Brooklyn, in the county of Kings and State of New York, have invented, made, and applied to use a certain new and useful Improvement in Pressing and Shaping Hats and Bonnets; and I do hereby declare the following to be a full, clear, and exact description of my said invention, reference being had to the annexed drawings, making part of this specification, wherein—

Figure 1 is a vertical section of the apparatus employed by me as in use. Fig. 2 is a plan of the rim-block.

Similar marks of reference denote same parts.

Heretofore in the manufacture of felt hats it has been usual to give to the cone a general form while wet, usually known as "wet-blocking." The hat is stiffened, and then goes to the bench blocker and finisher, who stretches the felt body over a crown-block, the band of which is varnished with shellac. The body is held on the block by a cord while the shellac sets. He steams it from time to time, pulls out the brim, and irons it until he brings it into proper shape. This is a laborious and expensive operation, and considerable time is lost in steaming the hat to make it sufficiently soft and moist for working, and this steaming is usually repeated several times, because the hat gets dry or cold, and the sizing sets before the hat can be completely shaped. After the hat has been thus blocked it is pounced, finished, and trimmed.

The nature of my said invention consists in a brim-ring to which the edge of the fabric is firmly connected while the crown is stretched by a crown-block, the fabric being softened by moisture and steam, so that it is brought to shape at one operation, and retained in that shape until sufficiently cool or dry. Thereby I am enabled in one operation to perform in a perfect manner what has heretofore required at least two tedious and laborious operations by hand or complicated machinery.

In Letters Patent granted to me September 20, 1864, a concave die with pins around its edge is shown.

My present invention has the said Letters Patent for a foundation, and is a more full development of the invention therein set forth.

In the drawings, *a* is a steam-box, to which steam is introduced in any desired manner. *b* is the brim-ring, with pins around its edges, as in aforesaid patent, or other means for holding the felt cone or other material, for forming the hat.

The steam being introduced heats and moistens the material previously stiffened or unstiffened, and then the crown-block *c* is introduced and pressed down to place by a lever or other suitable mechanism, which gives a complete shape to the hat. The block *c* is to be held in place by any suitable means until the hat is sufficiently dry and hard to retain its shape. To effect this I prefer and use the brim-block *d*, which also aids in smoothing the brim, and when the brim-ring *b* and block *d* are connected by clamps or other device the block *c* is thereby held in place, and the hat and blocks are removed and set aside to allow the hat to cool and dry while another hat is being shaped and blocked by separate blocks, as before.

A cross-bar or yoke might be applied to hold the crown-block in place, said cross-bar being connected at its ends to the brim-ring, so that the parts can be removed from the steam-box to cool and dry. If this mode of construction is adopted the hat crown and brim will be exposed on one side to the air, which will facilitate drying.

It may not be indispensable that the hat be shaped and blocked directly over the steam-box, as the fabric might be steamed and then shaped by the said ring and block before becoming dry or cool. A ring, *e*, upon the top of the steam-box *a* may be made movable and provided with hooks to take the brim-block *d* and hold that to the brim-ring *b*.

In order to cause the hat to adhere to the crown-die for finishing the same upon a lathe, I employ shellac applied to the surface of the block, as the varnish adheres to the inside of the hat-crown when it is separated from the block by the usual method.

If the hat is made with a bell-crown by an expanding crown-die, the brim-ring should be made in two pieces, so that it can be opened to take it off the hat.

By this mode of shaping and pressing hats, bonnets, and other articles to be worn upon the head, I am enabled to effect a great sav-

ing in time and cost, and the fabric is left in a much better condition than it would be if pressed between heated dies acting upon the entire surface. Besides this the hat or bonnet can be shaped at once into almost any form desired, the dies being constructed to produce that shape, thus enabling me to make articles that would be unusually costly when made by hand.

What I claim, and desire to secure by Letters Patent, is—

1. The ring brim-block *b*, to which the edge of the felt or other material is to be connected by pins or otherwise, in combination with the crown-block applied to stretch the fabric to shape, as set forth.

2. In combination with the brim-ring and

crown-block, the brim-block, or its equivalent, to connect the brim-ring and crown-block, so that they may be removed and retain the hat or similar article while cooling or drying, as set forth.

3. The method herein specified of forming or shaping hats and bonnets by heating and softening the felt or other material by steam, and then stretching and shaping said fabric at one operation by blocks before it cools or dries, substantially by the means set forth.

Dated this 27th day of April, A. D. 1866.

WM. E. DOUBLEDAY.
